Inventor:

C. M. Bryan.

UNITED STATES PATENT OFFICE.

C. M. BRYAN, OF WRIGHT CITY, MISSOURI.

IMPROVEMENT IN PLOWS.

Specification forming part of Letters Patent No. **23,898**, dated May 10, 1859.

To all whom it may concern:

Be it known that I, C. M. BRYAN, of Wright City, in the county of Warren and State of Missouri, have invented a new and useful Improvement in Plows; and I do hereby declare that the following is a full, clear, and exact description of the same, reference being had to the annexed drawings, making a part of this specification, in which—

Figure 1 is a perspective view of the main portion of a plow constructed according to my invention; Fig. 2, an inverted plan of the same. Fig. 3 is a detached back or inner side view of the mold-board.

Similar letters of reference indicate corresponding parts in the several figures.

This invention relates to an improvement in that class of plows which have reversible mold-boards with a share at either end, so that both may be used, one share as it becomes dull or worn out being displaced by reversing the mold-board and the other one properly adjusted for use.

The invention consists in the peculiar arrangement of the parts or the method of attaching or applying the mold-board, as hereinafter fully shown and described, whereby the mold-board may be readily adjusted or shifted on the plow and at the same time firmly secured to it, so as to prevent the possibility of the casual movement of the mold-board.

To enable those skilled in the art to fully understand and construct my invention, I will proceed to describe it.

A represents the beam of a plow, B the standard, and C C' the two handles.

D is the mold-board, which may be of the usual curved form, and having a share, a, formed on both its upper and lower ends, as shown clearly in Fig. 1, both shares being precisely alike both as regards form and dimensions.

To the back or inner side of the mold-board D two flanges, b b, are attached at opposite sides of the mold-board and at opposite ends. These flanges have the same position with the edge of the mold-board to which they are attached, and the position is such that either flange will, when the share a directly in front of it is at the lower end of the mold-board, be in line with the landside E. The back end of the

landside E is attached to the lower end of the handle C by a bolt, c, and a curved bar, d, which is attached at one end by a bolt, d', to the mold-board, passes through an eye, e, at the lower end of a rod, F, and is secured permanently to the landside E. The rod F extends upward through the standard B and beam A, and has a screw-nut, f, on its upper end. A bolt, g, also passes through the mold-board D and standard B. The lower flange, b, is secured by two screw-bolts, h h, to the front part of the landside, and the handle C' is secured to the upper flange, b, by screw-bolts i i.

From the above description it will be seen that the mold-board D is secured to the plow by the bolts h h, i i, g, and d', the bar d serving as a brace to render the mold-board perfectly rigid. When one share a becomes worn by use the bolts h h, g, i i, and d' are removed, and the mold-board is reversed or inverted so as to bring the uppermost share a downward, and the bolts h are inserted in the holes that were formerly occupied by the bolts i i, and the bolt d' passes through the hole formerly occupied by bolt g, the holes that receive the bolts g d' being made in the mold-board with a view to this adjustment of the mold-board.

The chief difficulty hitherto attending the construction of plows with reversible mold-boards has been the connecting of the mold-board to the plow in a rigid manner, and at the same time permitting the mold-board to be readily adjusted or reversed on the plow. This difficulty has been fully overcome by my invention.

I do not claim broadly the employment or use of a reversible mold-board, for they have been previously used and arranged in various ways; but

I do claim as new and desire to secure by Letters Patent—

Attaching the mold-board D by means of the bolts h h i i, passing through cleats b b at the inner side of the mold-board and into the landside E, and handle C', the bolts g d', and the brace-bar d, the whole being arranged substantially as and for the purpose set forth.

C. M. BRYAN.
